UNITED STATES PATENT OFFICE.

GUSTAV V. KARLSON, OF ELIZABETH, NEW JERSEY, ASSIGNOR TO CHILLINGWORTH ENGINEERING CORPORATION, A CORPORATION OF NEW YORK.

SIGNAL FLASHER.

Application filed January 6, 1922. Serial No. 527,398.

To all whom it may concern:

Be it known that I, GUSTAV V. KARLSON, a citizen of the United States, residing in the city of Elizabeth, in the State of New Jersey, have invented certain new and useful Improvements in Signal Flashers, of which the following is a specification, reference being had to the accompanying drawings, forming a part hereof.

10 Signal flashers have been extended from their use in marine fields to traffic work on land. For economy in initial cost, installation and up-keep it is generally recognized that gas is the most desirable lighting medium. However, no commercially practicable or satisfactory mechanical control for the flame characteristic has been proposed, most of the efforts being confined to some sort of magnetic or electrical control in order to obtain that degree of adjustment and latitude of control which is necessary. The principal object of the present invention is to provide a signal flasher in which gas is used as a lighting medium which shall have 15 all of the attributes suggested above and satisfy manufacturing requirements. More particularly, the invention has for its object to provide mechanical devices for opening and closing the gas channels which determine the delivery, in time and quantity, of the gas which supplies the flame. Still another object is to provide in association with simple mechanical control devices for the valves of such channels, a positive hand operated adjustment of simple form for changing at will the characteristics of the flame through increasing or decreasing either the period of darkness or the period of light. All of the control elements and adjustments 20 are quick and sensitive in action and give the desired results with a minimum of wear.

Still another object of the invention is to provide in a pressure control for a signal flasher operating mechanism for the valves 25 which includes a diaphragm movable, under all adjustments, for an equal distance above and below its median line.

Other objects of the invention having to do with other features whereby the improved flasher is made particularly adaptable for general uses will appear hereinafter in connection with the description of the accompanying drawings, wherein—

Figure 1 is a view partly in section and

partly in elevation of the improved flasher, 55 the interior of the gas chamber with the valve controlling parts being shown.

Figure 2 is a fragmentary view in side elevation of the burner showing its support and the gas connections. 60

Figure 3 is a detail view in vertical section through the gas chamber and showing the gas valves and the control mechanism therefor and the pressure diaphragm, the view being taken along the plane indicated 65 by the line 3—3 of Figure 4 and looking in the direction of the arrows.

Figure 4 is a view in plan of some of the parts shown in Figure 3, other parts, including the diaphragm, being removed in the 70 interest of clearness.

Figures 5 and 6 are detail views showing in section the mechanical operating devices for the gas valves in two extreme positions.

The base *a* of the flasher is of suitable 75 form and dimensions depending upon the situation in which it is to be placed and supports the gas chamber *b* which is closed by means of a flexible diaphragm *c* which may be clamped in place conveniently by means of a removable ring *d* secured to the upper edge of the chamber by means of bolts *e*. The gas which, for instance, may be acetylene is led into the gas chamber through any 80 convenient piping, a supply line *f* being indicated conventionally in the base *a*. From this supply line the gas may flow through a pipe *f'* past the needle valve *g* through a channel *b'* in the wall of the gas chamber *b* and past an inlet valve *h* which controls 85 its flow into the gas chamber. From the chamber the gas may escape past an outlet valve *i*, channel *b*² in the wall of the chamber *b* and pipe *k* to the burner *l* where it may be ignited by a pilot flame maintained 90 through an independent gas supply line *m*. *m'* which may derive a limited supply of gas from the supply line *f*, as indicated in Figure 1. The diaphragm may be completely enclosed within a cover plate *n* which 100 may be secured on the clamping ring *d*. On the inner face of this cover plate is seated a suitable spring *o* which engages the diaphragm *c* adjacent its axis to oppose upward movement of the diaphragm under the 105 pressure of the gas within the chamber *b*. The cover *n* may carry therewith an upwardly extending sleeve *n'* in which is slid-

ably mounted a supporting stem l' for the burner l . The elevation of the burner may be adjusted by means of a clamping screw n^2 which is carried with the sleeve n' and 5 co-operates with the stem l' to lock it releasably in adjusted position.

The principal feature of the invention is concerned with the mechanical actuating devices which are associated with the inlet and 10 outlet gas valves h, i respectively and open and close them at predetermined times in accordance with an adjusted flame characteristic. These mechanical actuating and adjusting devices are extremely simple in 15 construction and setting, and positive and quick in action. The valves h, i are swiveled to the underside of a bar p which is pivoted adjacent its mid-section on anti-friction bearing points p' disposed at opposite 20 sides of its mid-section. The valve bar p may be pressed on its bearings yieldingly by means of spring-pressed plungers p^2 seated on and guided by straps p^3 under which lie the bearing points p' . The valves h, i are 25 of the self-seating lap type and form a tight gas connection. Only one of these valves is intended to be seated at a time since when the gas is flowing to the flame past the outlet valve i the inlet valve h must be held 30 closed in order that the period of light may be of predetermined duration. Contrariwise, when gas is flowing from the supply line f into the chamber b past the inlet valve h the outlet valve i will be seated so that 35 during the predetermined period of darkness the gas supply may be replenished. To secure a quick and positive seating and opening of the inlet and outlet valves h, i respectively by simple mechanical devices is a 40 problem which has not heretofore been satisfactorily solved. In the present invention these devices are extremely sensitive, positive, simple and quick acting so that the characteristics of the flame may be adjusted 45 with the greatest nicety.

The diaphragm c is the actuating element for the valves, its movement in one direction being caused by the spring o and its movement in the other direction being caused by 50 the pressure of the gas confined in the chamber b after its passage past the inlet valve h . Movements of the diaphragm c must be communicated to and impressed upon the controlling valves h, i . The elements for 55 transmitting these movements are of improved construction. They include ordinary arms q pivoted respectively on uprights q' fastened to the base of the gas chamber b . These arms overlie the valve bar p and 60 extend in substantial parallelism from one side of the pivot point p' therefor to the other. The free ends of the spring arms q are connected operatively to the valve bar p adjacent one end thereof through the devices illustrated most clearly in Figures 5 and 65

6. The bar p has mounted loosely therein but transversely thereof a bearing block p^4 , the opposite ends of which are recessed to afford bearing seats for short push rods r , the opposite ends of which may be tapered 70 to afford anti-friction engagement at their inner ends with the bearing block p^4 and, at their outer ends, with the bearing pieces s carried on the inner faces of the spring arms q opposite the bearing block p . The 75 bearing pieces s on the arms q may constitute the heads of the studs s' which may be threaded through the arms and extend outwardly therefrom to act as stops which co-operate with the heads of studs t threaded into posts 80 t' to limit the travel of the arms q up and down. The push rods r are of such length with respect to the floating bearing block p^4 and the distance between the spring arms q that they may pass through their dead centers without imposing undue stresses on any of the associated parts and yet effect a quick and positive change in position of the pivotal valve bar p . The spring arms q are 85 yieldable laterally and it is their tension 90 which snaps the valve bar p upwards or downwards as the push rods r pass through their dead center. The floating block p^4 accommodates itself laterally to unbalanced 95 stresses thereon from one side or the other 100 and insures a floating connection between the spring arms at all times. Movement of the valve bar p about its pivot point p' is in a direction opposite from the direction of movement of the spring arms q which is to 105 say that when the ends of the arms q are raised, as shown in Figure 5, the proximate end of the valve bar p is forced downwardly to seat the inlet valve h . On the other hand, when the free ends of the spring arms q are 110 lowered, as shown in Figure 6, the action of the push rods r is to force the proximate end of the valve bar p upwardly, thus unseating the valve h and forcing the outlet valve i at the opposite end to its seat. In their movements the arms q carry the studs s' for co-operation with the limit stops t, t' .

In a construction in which equal and opposite movements at all times of the diaphragm c would give the desired flame characteristic, a direct connection between the diaphragm and the arms q might be effective to accomplish the intended purposes. However, in the illustrated embodiment it is proposed to connect the diaphragm operatively with the spring arms q through adjustable means whereby the flame characteristics as regards both periods of light and periods of darkness may be delicately controlled. At the center of the diaphragm c 115 are connected, in accordance with usual practise, metal discs c' united by a central stud c^2 threaded therethrough. The stud c^2 carries at its lower end a loose rocking trunnion block c^3 through which passes the 120 125 130

end of a lever q^2 carried by a transverse pivot pin q^3 journaled in the spring arms q . The free end of the rod q^2 extends into a bell shaped head u on an adjustable stud u' threaded through the side wall of the gas chamber b and lying in substantial prolongation of the rod q^2 in the median position of the latter. The end of the rod q^2 which co-operates with the inner tapered walls of the bell shaped head u may be formed with an anti-friction bearing ball q^4 . The exposed end of the stud u' may be formed for engagement by a suitable tool, such as v , to facilitate rotation of the stud 10 although the invention is not to be limited to this detail.

In the initial setting of the flasher it will be understood that the rate of flow of the gas into the chamber will be determined 20 within satisfactory limits by adjusting the needle valve g . The gas flowing into the chamber past the valve h will exert a pressure on the diaphragm c and force it upwardly. The stud c^2 will carry the lever q^2 up with it until the ball q^4 seats against the tapered face of the bell shaped head u and constitutes a fulcrum about which the pressure may be transmitted through the rod q^2 to the pin q^3 and the spring arms q in 25 which it is journaled. Upward movement of the arms q about their pivotal supports q' will continue until the push rods r against the lateral tension of the arms q snap through their dead centers and, under the tension of 30 the arms q , force the proximate end of the valve bar p downwardly to seat the inlet valve h . Simultaneously and with the same snap the outlet valve i will be plucked from its seat and the gas within the chamber will 35 flow through the feed pipe n' to the burner l where it will be ignited by the pilot flame from the other line m, m' . As the gas flows out of the chamber b the diaphragm c will 40 be forced downwardly under the influence of the spring o , the arms q swinging downwardly therewith by reason of their pivotal connection thereto through the pin q^3 and the rod q^2 . When the push rods r are 45 carried past their dead center the tension of the spring arms q will be transmitted through them to the proximate end of the valve bar p so as to force the latter upwardly about its pivot points p' , its up position being illustrated in Figure 6. Incidentally the outlet valve i will be seated and the inlet valve h plucked from its seat. 50 The period of darkness may be adjusted to a fraction of a second by moving the bell shaped head u towards or away from the end q^4 of the rod q^2 , it being understood that the instant when the inlet valve h is moved to its seat and the outlet valve i opened depends, in the last analysis, upon the relation between the end q^4 and the remoteness 55 of its seat within the head u . As viewed in

Figure 3, if the head u is backed away from the end q^4 a longer time will elapse before the diaphragm c has moved a sufficient distance to engage the end q^4 with its seat. The time elapsing before the outlet valve 70 i is forced to its seat will contrariwise depend on the relation of the bell head u and the end q^4 of the rod q^2 . In any event, it will be found that the movements of the diaphragm c from its median position upwards and downwards are always equal thereby insuring it a wide effective range of movement and relieving it of undue stresses such as are imposed when undue movement in one direction or the other is required. 75 Within limits, any desired relation between the period of light and the period of darkness may be brought about by regulating the needle valve g to give a faster or slower rate of inflow. 80

All of the mechanism described is at once very simple and accessible, positive and quick in action and readily adjustable. It is wholly of a mechanical character and the mechanical devices are extremely simple and not subject to excessive wear in spite of the delicate control afforded by them. Changes which have to do with mere matters of form, dimensions and arrangement may be made by 85 those skilled in the art without departing from the spirit of the invention. 95

I claim as my invention:

1. In a gas signal flasher, a pressure chamber, inlet and outlet valves to control the flow of gas to and from said pressure chamber, a rocking bar on which said valves are carried, a diaphragm movable by the gas, yielding lever arms connected operatively with the diaphragm and movable therewith, and push rods interposed operatively and pivotally connected to said arms and the bar to impress movements of the arms on the bar. 100

2. In a gas signal flasher, a pressure chamber, inlet and outlet valves therefor to control the flow of gas to and from said chamber, a rocking bar on which said valves are carried, a diaphragm movable under the action of the gas, yielding arms mounted pivotally and connected operatively to the diaphragm and a floating connection between the arms and the bar including a member carried loosely with the bar and push rods pivotally interposed between said member and said arms. 115

3. In a gas signal flasher, a pressure chamber, inlet and outlet valves to control the flow of gas to and from said chamber, a rocking bar mounted on anti-friction bearings and carrying said valves, a swiveled connection between said valves and said bar, a diaphragm movable under the action of the gas, spring arms mounted pivotally within the chamber and connected opera- 125 130

tively to the diaphragm, a member mounted loosely in the bar at one side of its pivot and push rods pivotally connected through anti-friction bearings to said member and said 5 arms.

4. In a gas signal flasher, in combination with a pressure chamber, self-aligning inlet and outlet valves to control the flow of gas into and out of said chamber, a diaphragm 10 movable at equal distances towards and away from its median line under the gas pressure to initiate operation of said valves and an adjustable connection between said diaphragm and said valves including a lever 15 having a spherical end and a conical seat therefor movable towards and away from the lever to change its fulcrum with respect to said diaphragm.

5. In a gas signal flasher, in combination 20 with a gas chamber, inlet and outlet valves to control the flow of gas into and out of said chamber, a bar on which said valves are carried, a diaphragm movable under the action of the gas to initiate operation of said 25 valves, and an adjustable connection between said bar and the diaphragm including pivoted yielding arms, push rods interposed operatively between said arms and said bar, a rod pivoted on said arms and 30 connected with said diaphragm and an adjustable fulcrum for said rod including a movable tapered seat for one end of said rod.

6. In a gas signal flasher, a gas chamber, 35 self-aligning inlet and outlet valves to control the flow of gas into and out of said chamber, a rocking bar on which said valves are carried, said valves being movable equal distances from their seats upon rocking of 40 said bar, a diaphragm movable equal distances towards and away from the median line under the pressure of the gas, and means operatively connecting said bar with said diaphragm to rock the bar upon equal

movements of the diaphragm in opposite directions from its median position. 45

7. In a gas signal flasher, a gas chamber, inlet and outlet valves to control the flow of gas into and out of the chamber, a rocking bar on which the valves are carried, said bar being pivoted at its mid-section to move the valves equal distances from their seats upon rocking, a pivoted arm connected with the bar, push rods included in said connection between the pivoted arm and the bar, 50 a rod pivoted on said arm, a diaphragm connected with the rod and movable under the gas pressure and an adjustable fulcrum for said rod and adapted to engage it in one position when the rod is horizontal and the diaphragm in the median position, the relation of said parts being such that in all 55 positions the diaphragm moves equal distances in opposite directions.

8. In a gas signal flasher, in combination 60 with a gas chamber, a supply line connected therewith, an adjustable hand valve to regulate the rate of flow of gas thereto, inlet and outlet valves within the chamber, a bar on which the valves are carried, a diaphragm 70 movable under the pressure of the gas, and operative connections between the diaphragm and the bar including a pivoted arm, push rods interposed operatively between the arm and the bar, a rod pivoted 75 on the arm and in swiveled engagement with the diaphragm, a bell shaped head in which one end of the rod extends, a threaded stem carrying the head and extending through the walls of the gas chamber for manual 80 rotation to change the relation of the head to the end of the rod and thereby vary the position of the fulcrum with respect to the diaphragm.

This application signed this 5th day of 85 January, A. D. 1922.

GUSTAV V. KARLSON.
